UNITED STATES PATENT OFFICE.

CHARLES P. ZIMMERMAN, OF NEWARK, NEW JERSEY, ASSIGNOR OF ONE-HALF TO ISAAC P. BROWN, JR., OF SAME PLACE.

AIR-HEATING-FURNACE RADIATOR.

SPECIFICATION forming part of Letters Patent No. 350,452, dated October 5, 1886.

Application filed December 4, 1885. Serial No. 184,683. (No model.)

To all whom it may concern:

Be it known that I, CHARLES P. ZIMMERMAN, a citizen of the United States, residing in Newark, Essex county, New Jersey, have 5 invented certain new and useful Improvements in Air-Heating-Furnace Radiators, fully described and represented in the following specification and the accompanying drawings, forming a part of the same.

10 This invention consists in the construction, herein shown and described, for a furnace-radiator.

The construction will be understood by reference to the annexed drawings, in which 15 Figure 1 is a plan of a furnace and an auxiliary air-chamber constructed as described. Fig. 2 is a side elevation of the same, the auxiliary air-chamber and the radiating-pipes being shown in section, as well as the smoke-20 pipe of the furnace, on line xx in Fig. 1; and Fig. 3 is a perspective view of the radiating-pipes and their supporting-base without the casing.

The improvement is represented as applied 25 to a portable furnace, A being the casing of the same, A' the top cone, and B B' the register-pipes for conveying the hot air from the furnace.

C is the base of the furnace, and D is a cold-30 air pipe connected thereto to supply fresh air to the heated surfaces within the casing.

E is the smoke-pipe of the furnace, which, instead of conveying the smoke directly to the chimney, conveys it through the radiating-pipes inclosed within the casing of the auxiliary air-chamber F, the latter being connected 35 with the cone A' by a discharge-pipe, F'.

G is the base of the chamber F, and a duct, D', connects it with the cold-air pipe D, and 40 has a damper, H, inserted in it to cut off such air-supply, if desired.

The construction which I preferably employ for the radiating-pipes is shown in perspective in Fig. 3, common earthen drain-pipe 45 being used to form upright tubes I, through which the hot air passes upward and downward, and earthen branch pieces being employed to connect the upright pipes together at the bottom and to the smoke inlet and out-50 let at the top.

J is the header receiving the smoke from the

nozzle J' upon the smoke-pipe E. K K' are the bottom headers, connected by integral cross-pipes L; and M is the header discharging the smoke into the nozzle J'', which is placed 55 on the smoke-pipe E, a sufficient distance from the nozzle J' to admit a damper, N, between the two. The pipes I are provided at their upper ends with the usual sockets, I', and the headers K K' are formed with sockets to receive 60 the lower ends of said pipes, the branches J M being formed with nozzles to fit into the sockets I', and the sockets all being tightly cemented with putty formed chiefly of plum-bago, which I find is adapted to endure the 65 temperature to which it is exposed. The ends of all the branch pipes are extended outside the casing, as shown in Fig. 1, to secure convenient access thereto for cleaning them out. As the headers J and M have no communication 70 with one another inside the air-chamber F, it is obvious that when the smoke is admitted to the header J it must pass downward and through the cross-pipes L to reach the header M. The opening of the damper N in 75 the pipe E thus permits a direct passage of the smoke from the furnace A to the chimney, while the closing of the damper N obstructs such direct passage and compels the smoke to traverse all the pipes of the radiator before 80 escaping to the chimney. Caps m are applied to all the exposed ends of the headers to close the same, except when cleaning, and a damper, O, is provided in the duct D' to cut off the supply of cold air to the casing F, and a 85 damper, P, is also inserted in the discharge-pipe F', to disconnect the auxiliary air-chamber from the top of the furnace.

The operation of this attachment is as follows: When the furnace fire is first lighted, 90 the damper O or P may be closed and the damper N opened, the smoke from the furnace then passing directly to the chimney without affecting the radiator. When the fire is sufficiently hot, the damper N is closed to drive the 95 smoke through the radiator, and the dampers O and P being closed a continuous current of cold air enters the base G, passes upward through holes g, circulates around the radiating-pipes and passes into the top of the furnace through the pipe F', the air thus supplied to the furnace being sufficiently warmed 100.

to require but little additional heat from the radiating-surfaces in the furnace to fit it for entering the register-pipes. If desired, a connection, Q, may be made from the air-chamber 5 F directly to one of the register-pipes, and the air warmed by the radiator may be permitted to supply such pipe exclusively, or with the aid of the furnace in connection therewith. In such a construction a damper, R, would be 10 inserted in the connection Q, to close it when the air from the chamber F was not sufficiently heated to supply a register, and a damper, S, would be inserted in the register-pipe to cut off the air from the furnace when it was supplied by the air-chamber F. The extending 15 of the ends of the branches outside the casing or walls of the chamber F permits the cleaning of the radiator without disconnecting any of its parts.

Having thus set forth my invention, it will 20 be seen that it affords a convenient means of utilizing the greater part of the heat which commonly escapes to the chimney, and that it may be readily disconnected from the furnace, 25 when desired, so as not to affect its ordinary operation. The furnace shown herein at A is of that cylindrical form in which no space exists at the side of the fire-pot to contain a radiator in which the gases can be traversed 30 back and forth in their passage to the chimney. The discharge of the heated gases from the furnace is therefore through short passages, and the gases are discharged from the furnace at quite a high temperature, and in such case 35 my auxiliary air-chamber is of great advantage.

I claim—

1. The combination, with a hot-air furnace,

of an auxiliary air-chamber containing vertical collared earthenware pipes having headers 40 connected together at one end of said pipes and disconnected at their opposite ends, the smoke pipe from the furnace being connected with both of said disconnected headers, and a damper being inserted in the smoke-pipe between its connections to said headers, so as when closed to direct the smoke and gases through the radiating-pipes, as and for the purpose set forth.

2. The combination, with a hot-air furnace, 50 of a discharge-pipe, B', an auxiliary air-chamber supplied with cold air and containing radiating-pipes connected with the smoke-pipe of the furnace, and the air-chamber being provided with a discharge-pipe leading to the top 55 of the furnace, a damper, P, in said discharge-pipe F', a connection, Q, to the register-pipe B', and a damper, R, in such connection, as and for the purpose set forth.

3. The combination, with the furnace A, 60 an auxiliary air-chamber, F, containing radiating-pipes connected with the smoke-pipe of the furnace, of the cold-air pipe D, supplying the base of the furnace, the duct D', supplying the base of the air-chamber, the damper 65 O in the said duct, and a discharge-pipe from the top of the air-chamber, as and for the purpose set forth.

In testimony whereof I have hereunto set my hand in the presence of two subscribing 70 witnesses.

CHARLES P. ZIMMERMAN.
